UNITED STATES PATENT OFFICE.

STEPHEN GORMAN AND WILLIAM H. C. WARD, OF BUFFALO, NEW YORK.

SPARK PLUG.

Application filed June 28, 1923. Serial No. 648,174.

To all whom it may concern:

Be it known that we, STEPHEN GORMAN and WILLIAM H. C. WARD, citizens of the United States, residing at Buffalo, in the 5 county of Erie and State of New York, have invented certain new and useful Improvements in Spark Plugs, of which the following is a specification.

In carrying out the present invention, it 10 is our purpose to provide a spark plug, wherein carbon or oil deposits upon the electrodes of the plug will be prevented.

We accomplish the above purpose by providing a main electrode having a passage 15 extending longitudinally therethrough, whereby upon the intake stroke of the engine piston, a supply of air will be drawn therethrough, for consequently blowing off carbon or oil deposits from the electrodes, the plug 20 also including novel means for preventing the discharge of the gases through said main electrode.

Yet another object of the invention is to provide a plug of the above character that 25 is comparatively simple of construction, and one that may be manufactured and marketed at but slightly greater cost than plugs now universally used.

The nature of the invention will be better 30 understood when the following detailed description is read in connection with the accompanying drawing, the invention residing in the construction, combination, and arrangement of parts as claimed.

35 In the drawing forming a part of this application, like numerals of reference indicate similar parts in the several views, and wherein:

Figure 1 is a detail vertical cross section 40 of our improved plug.

Figures 2 and 3 are cross sections through certain of the elements included in our plug.

Figure 4 is a top plan view of a still further element comprising a component part 45 of the plug, and

Figure 5 is a vertical cross section thereof.

Our novel plug embodies a shell 5 of conventional form, which is formed at its lower end with an inwardly bent electrode 6 that 50 is adapted for receiving a well known form of porcelain 7, and that is maintained within said shell by a packing gland 8.

Within the porcelain 7 and extending therethrough is a main electrode 9, that is 55 formed centrally with an air passage 10 that is of a length equivalent to the length

of said electrode. This electrode 9 is formed with a flange 11 that contacts the usual shoulder formed at the upper end of the usual skirt portion upon said porcelain 7 60 for obvious purposes.

The upper end of the electrode 9 is externally screw threaded as shown in Figure 1, for receiving the usual thumb nut 12, whereby the terminal wire of the ignition 65 circuit may be secured thereto.

In screw threaded engagement upon said screw threaded end of the electrode 9 above the thumb nut 12 is a fitting designated generally 13, which comprises a neck portion 70 14, Figure 5, and a circular head portion 15. Extending centrally through said neck portion as well as the head portion of the fitting is an opening that is internally screw threaded at the portion within the neck 14 75 for engagement upon the screw threaded end of the electrode. The head 15 of this fitting is formed at one side with a well 16, the lower end of which is formed with an orifice 17, that is so shaped as to provide a seat 80 for a ball valve 18, Figure 1.

Surrounding the head 15 of said fitting 13 is a ferrule 19, that is preferably shrunk upon said head, and is provided internally 85 adjacent its upper end with a circular flange 20, upon which is positioned a disk 21, and maintained in engagement therewith through any manner desirable.

The electrode 9 is provided at a point 90 within the usual skirt portion of the porcelain 7 with passages 22, that communicate with the air passage 10 in the electrode, and in view of the above description when considered in conjunction with the accompanying drawings, it will at once be apparent 95 that in operation, either will be drawn through the main electrode 9 during the intake stroke of the engine piston for consequently projecting a blast of air upon the secondary electrode 6, as well as within the 100 skirt portion of the porcelain 7, for thereby preventing carbon or oil deposits. The gases will be prevented from escaping through the main electrode by the ball valve 18, and even though we have herein set forth 105 the most practical embodiment of the invention with which we are at present familiar, it is nevertheless to be understood that minor changes may be made therein, without departing from the spirit and scope of 110 the invention as claimed.

Having thus described our invention, what

we claim as new, and desire to secure by Letters Patent, is:

A spark plug comprising a body having an electrode, a second electrode passing through the body and provided with a duct extending from end to end thereof, the inner end of the duct being disposed opposite the electrode which is carried by the body, valve means for controlling the admission of air and applied to the outer end of the second mentioned electrode and the duct thereof,

the second mentioned electrode being provided at points within the body of the spark plug with transversely disposed ducts which communicate at their outer ends with the interior of the plug, and at their inner ends with the first mentioned duct at points between the ends thereof. 15

In testimony whereof we affix our signatures.

STEPHEN GORMAN.
WILLIAM H. C. WARD.
